UNITED STATES PATENT OFFICE.

WILLIAM SEIFERT, OF SCHENECTADY, NEW YORK.

PERPETUAL CALENDAR.

Application filed December 20, 1921. Serial No. 523,752.

To all whom it may concern:

Be it known that I, WILLIAM SEIFERT, a citizen of the United States, residing at Schenectady, county of Schenectady, State 5 of New York, have invented certain new and useful Improvements in Perpetual Calendars, of which the following is a specification.

The present invention relates to perpetual 10 calendars, particularly those of the type adapted to be arranged on a pencil, pen, or other cylindrical device, and has for its object to provide a new and improved structure and arrangement in a calendar of this 15 character.

For a consideration of what I believe to be novel and my invention, attention, is directed to the accompanying specification and the claim appended thereto.

20 In the drawing, Fig. 1 is a side elevation showing a pencil provided with a calendar embodying my invention; Fig. 2 is a developed view of the cylindrical members which comprise the calendar, and Fig. 3 is a 25 sectional view showing the calendar arranged on a pencil holder.

Referring to the drawing, my calendar comprises three cylindrical parts or portions 5, 6 and 7. The parts or portions 5 and 7 30 are fixed and the part or portion 6 which lies between them is in the form of a cylindrical sleeve which is free to turn but is held from axial movement.

The part 5 is divided into seven spaces 35 by transversely extending lines 8 and in these spaces are arranged the names of the twelve months of the year in the order shown, viz. May, January and October; April and July; September and December; 40 June; February, March and November; and August.

The part 6 is divided into seven vertical columns by transversely extending lines 9 and into a plurality of circumferential rows 45 by lines 10. Lines 9 have the same spacing as do lines 8. The circumferential row next adjacent part or portion 7 contains the names of the days of the week in its seven spaces. The other rows contain the years arranged in numerical order, leap years being put down in two successive spaces. The numbers of the years are arranged in the first row, then step up into the next row and so on for as many rows as it is desired to

supply years. The calendar is shown as beginning with the year 1921 and reading the numbers around it will be seen that in what may be considered the first row, i. e., the row next to the days of the week are the years 1921, 1922, 1923, 1924, (in red), 1924, 1925, 1926. The years then step up into the next row wherein is found 1927, 1928 (in red), 1928, 1929, 1930, 1931, 1932 (in red). The next row contains 1932, 1933, 1934, 1935, 1936 (in red), 1936, 1937. In the same manner there may be additional rows as found desirable.

The part or portion 7 is divided by transversely extending lines 11 and circumferentially extending lines 12 into rows of 70 seven spaces each containing the numbers 1 to 31 in order, being the days of the months. Below this is a space 13 containing directions for the use of the calendar. In the present instance, it is assumed that the figures and names are black, with the exception of leap years which occur twice, the first time in red and the second time in black and in Fig. 2 I have indicated the red years by larger numerals marked with a star. It 80 will be understood, however that this is only by way of example and that any suitable distinguishing arrangement may be used.

In use it is only necessary to turn the cylindrical part or portion 6 to bring the 85 particular year in line with the particular month, the red years being used for January and February. The portion 7 in connection with the days of the week on portion 6 form a calendar for the particular month. In the 90 present instance in Fig. 2, the calendar is set for the month of December, 1921, the first day of the month being Thursday, and the four Sundays occurring on the 4th, 11th, 18th, and 25th.

It will be understood that my improved calendar may be put on a special cylindrical holder or carrying member or it may be put on a pencil, a pen, a pencil holder or other device. In the present instance I have shown 100 it in Fig. 1 arranged on a metallic lead pencil 15 and in Fig. 3 arranged on a pencil holder 16. The parts or portions 5, 6 and 7 may be formed from any suitable material such as celluloid, embossed paper, or the like 105 and it will be seen from Fig. 3 that the adjacent ends of parts or portions 5 and 7 form shoulders which serve to hold part or

portion 6 from axial movement. Part or portion 6 may be arranged so there is more or less friction which tends to prevent its turning easily so that it will stay in any 5 adjusted position.

It will be seen that my improved calendar is very simple in structure, comprising but three parts or portions and only one movable part, and that to use it requires no 10 complicated adjustments, it being only necessary to turn the cylinder 6 to bring the year into line with the month. This means that the calendar is thoroughly practical for use by every one, for it requires no effort, 15 skill or study to use it. Furthermore, it may be made small and compact so it takes up but little room in an axial direction and it can be manufactured at a low cost. As is obvious, the calendar may be manufactured as 20 a part of a pencil, pen or the like or it may be supplied separately and applied as an accessory.

In accordance with the provisions of the patent statutes, I have described the principle of operation of my invention, together 25 with the apparatus which I now consider to represent the best embodiment thereof, but I desire to have it understood that the apparatus shown is only illustrative and that 30 the invention may be carried out by other means.

What I claim as new and desire to secure by Letters Patent of the United States, is:—

The combination with a cylindrical carrying member of a band fixed thereon divided 35 into seven spaces containing the names of the months of the year, the first space having "May" in it, the second space "January" and "October," the third space "April" and "July," the fourth space "September" and 40 "December," the fifth space "June," the sixth space "February," "March" and "November" and the seventh space, "August," a second band fixed on the carrying member in spaced relation to the first and divided into circumferential rows each having seven spaces, 45 the spaces containing the figures 1 to 31 inclusive, the figure 1 being in line with "May" on the first band, and a third circumferentially adjustable band arranged on the 50 carrying member between the first two bands, said third band being divided into a plurality of circumferential rows of seven spaces each, the row adjacent the second named band containing the days of the week 55 and the other rows containing the years, leap years occurring twice and in distinctive figures whereby the calendar may be set by adjusting a single band only.

In witness whereof, I have hereunto set 60 my hand this 15th day of December, 1921.

WILLIAM SEIFERT.
